UNITED STATES PATENT OFFICE

DONALD W. SHERMAN, OF MILWAUKEE, WISCONSIN, ASSIGNOR TO A. O. SMITH CORPORATION, OF MILWAUKEE, WISCONSIN, A CORPORATION OF NEW YORK

DRAFTING TABLE

Application filed April 30, 1931. Serial No. 533,927.

The invention relates to a drafting table. The drafting table to which the invention applies in particular has a pivoted table top supported on legs arranged in pairs at each end.

An object of the invention is to provide a drafting table which is readily adjusted to the floor to keep the table from tilting.

Another object is to provide a table which is rigidly braced in a forward and rearward direction and endwise.

Another object is to provide the table with a table top which is braced against torsional stresses to prevent distortion of the table top by warping or twisting.

Another object is to provide a table with a table top which may be readily adjusted in either a vertical or horizontal position.

Another object is to provide a table which may be readily assembled or disassembled.

Another object is to provide a table which is simple in construction.

Another object is to provide a table which may be economically manufactured.

According to the invention as ordinarily embodied in practice, the table is provided with legs pivoted in pairs at each end to permit each pair of legs to turn or oscillate relative to the other pair to adjust the legs to the floor and keep the table from tilting.

The invention is embodied in the accompanying drawings in which the views are as follows:

Fig. 1 is an elevational view of the table.

Fig. 2 is a partial elevational view, on an enlarged scale, of the pivoted connection between the table top and the legs.

Fig. 3 is a sectional view on the line 3—3, Fig. 2.

Fig. 4 is an end view of the table.

Fig. 5 is an end view of a table showing the legs in a modified form.

The table top 1 has fastened on its underside cross-braces or cleats 2, and fastened to alternate cleats are brackets 3.

The brackets are arranged on an elongated tubular bar 4 extending endwise of the table, and each bracket has a clamping ring 5 held by a screw 6, by which the bracket is normally kept rigidly clamped to the bar.

The bar is of sufficient diameter to have torsional rigidity, and when the brackets are clamped in fixed position upon the bar, the table top is braced by the brackets and the bar against stresses in substantially all directions to prevent distortion of the table top by warping or twisting.

The table has its legs arranged in pairs at each end, each pair being spread at the bottom and converging toward the top to brace the table in a forward and rearward direction, and having a suitable tie-rod 7 to provide rigidity in each pair.

Each leg is formed by struts 8 spaced apart at the top and converging toward the bottom to brace the table endwise, the struts being prevented from spreading by suitable tie-rods 9.

Formed at the apex of each pair of legs are two axially spaced clamping rings 10 and 11 by which each pair is pivoted to the bar 4 to turn or oscillate relative to the other pair and thereby all the legs are brought into bearing upon the floor.

One of the clamping rings 10 is held by a screw 12 to have a yielding frictional grip upon the bar 4 to allow the table top 1 to be adjustably tilted, and the other clamping ring 11 is held by a screw-bolt 13 provided with a handle 14 to firmly grip the bar and keep the table top in a fixed position.

The table may be readily disassembled for transportation or storage by removing the table top 1 from the brackets 3 and loosening the leg and bracket clamping rings, sliding the bar 4 out of the rings.

In Fig. 5 is shown a modified construction of the legs which permits the table top to be tilted to substantially a vertical position.

The front leg 15 extends downward in nearly a vertical position and is supported at the foot thereof by an inclined brace 16, which bears upon the floor at its lower end and is connected to the rear leg 17 at its upper end.

The invention is susceptible of various modifications without departing from the scope thereof, as hereinafter claimed.

The invention is hereby claimed as follows:

1. A table, comprising a table top, legs

100

formed by struts spaced apart at the top and converging toward the bottom, said legs being arranged in pairs at each end of said table top and pivotally connected thereto to permit each pair to turn or oscillate relative to the other pair to adjust the legs to the floor.

2. A table, comprising a table top, a longitudinal bar, brackets secured to said table top on the under side thereof and connected by said bar to brace the table top against torsional stresses in substantially all directions, and a pair of legs arranged at each end of said table top and pivotally connected thereto to permit each pair of legs to turn relative to the other pair to adjust the legs to the floor, each leg being formed by struts spaced apart at the top and converging toward the bottom to brace the table endwise.

3. A table, comprising a table top and a pair of legs arranged at each end thereof and pivotally connected to said table top to permit each pair to turn or oscillate relative to the other pair to adjust the legs to the floor, the front legs in each pair being disposed nearer the vertical than the rear legs to permit the table top to be tilted in a substantially vertical position.

4. A table, comprising a table top and a pair of legs arranged at each end thereof and pivotally connected to said table top to permit each pair of legs to turn or oscillate relative to the other pair to adjust the legs to the floor, each leg being formed by struts spaced apart at the top and converging toward the bottom to brace the table endwise and the front legs in each pair being disposed nearer the vertical than the rear legs to permit the table top to be tilted to substantially a vertical position.

40. 5. A table, comprising a table top, a longitudinal bar, brackets secured to said table top on the under side thereof and connected by said bar to brace the table top against stresses in substantially all directions, a pair of legs arranged at each end of said table top and pivotally connected thereto to permit each pair to turn relative to the other pair to adjust the legs to the floor, each leg being formed by struts spaced apart at the top and converging toward the bottom to brace the table endwise, means to yieldingly clamp said table top against movement to permit said table top to be adjustably tilted, and means to lock said table top in a fixed position.

55. 6. A table, comprising a table top, a longitudinal bar, brackets secured to said table top on the under side thereof and connected by said bar to brace the table top against torsional stresses in substantially all directions, a pair of legs arranged at each end of said table top and pivotally connected thereto to permit each pair to turn or pivot on a horizontal axis and relative to the other pair to adjust the legs to the floor, each leg being formed by struts spaced apart at the top and

converging toward the bottom to brace the table endwise, means to yieldingly clamp said table top against movement to permit said table top to be adjustably tilted, and means to lock said table top in a fixed position.

7. A drafting table comprising a table top, a pair of legs pivotally connected to said table top adjacent the ends, each leg being formed of struts which diverge longitudinally of the table as they approach the top to brace it against end thrusts and transversely of the table top as they approach the bottom to brace it on a floor, and means for setting the table top in different angular positions relative to the horizontal.

8. A drafting table comprising a table top, a plurality of bearing brackets depending from the table top, a bar rotatably mounted in the brackets, legs for supporting the bar, rings provided on each leg in which the bar may be rotatably mounted, the rings on each leg being spaced longitudinally of the bar to brace it against endwise thrusts, the legs diverging transversely of the table top from the bar toward the bottom adapting them to seat firmly on any foundation, and means for setting the table top bar and legs in different predetermined relative positions.

9. A drafting table comprising a table top, a plurality of cleats extending transversely of the table top, bearing brackets depending from alternate cleats, a bar rotatably mounted in the bearing brackets, the bar and cleats serving to brace the table against torsional stresses in substantially all directions, the legs diverging outwardly longitudinally of the bar from the bottom upwardly, rings provided on the diverging legs to receive the bar, the rings being spaced longitudinally of the bar to brace it against endwise thrusts, the legs diverging transversely of the table top from the top downwardly to adapt them to seat firmly on the floor, set screws in the bearing brackets, and rings carried by the legs for setting the table top in different angular positions to the horizontal.

In witness whereof, I have hereunto subscribed my name.

DONALD W. SHERMAN.
